United States Patent Office

Des. 183,156
Patented July 8, 1958

183,156

COMBINED BATH TUB AND BASIN

Ernest Amerio, New York, N. Y.

Application November 26, 1957, Serial No. 48,684

Term of patent 14 years

(Cl. D4—4)

FIG. 1.

FIG. 2.

FIG. 3.

Fig. 1 is a side elevational view of a combined bathtub and basin, showing my new design;

Fig. 2 is a rear elevational view thereof;

Fig. 3 is a perspective view thereof.

I claim:

The ornamental design for a combined bathtub and basin, as shown.
